(57) **CLAIM**

The ornamental design for a scoop, as shown and described.

DESCRIPTION

FIG. 1 is a front, left side perspective view of a scoop showing our new design.

FIG. 2 is a left side view thereof, the opposite side being a mirror image.

FIG. 3 is a top plan view thereof.

FIG. 4 is a bottom plan view thereof.

FIG. 5 is a rear view thereof; and,

FIG. 6 is a front view thereof.

The dash-dash broken lines are for illustrative purposes only and form no part of the claimed design. The dot-dash broken lines immediately adjacent the solid lines represent a boundary between claimed and unclaimed subject matter and form no part of the claimed design.
